MENSUAL CALCULATOR

Suzy T. Gluck, 1114 Pine Drive, Beverly Hills, Calif. 90210, and Jack K. Beck, 19145 Schoenbron St., Northridge, Calif. 91324

Filed May 15, 1970, Ser. No. 23,002

Term of patent 14 years

Int. Cl. D10—99

U.S. Cl. D52—6

FIG. 1.

FIG. 2.

FIG. 3.

FIG. 4.

FIG. 1 is a top plan view of a mensual calculator, showing our new design;

FIG. 2 is a side elevational view thereof;

FIG. 3 is a bottom plan view thereof; and

FIG. 4 is a fragmentary sectional view, on an enlarged scale taken on arrows IV-IV of FIG. 1.

We claim:

The ornamental design for a mensual calculator, substantially as shown.
